UNITED STATES PATENT OFFICE.

ARTHUR C. PRINCE, OF CHICAGO, ILLINOIS.

POCKET BANK AND LOCKING MEANS THEREFOR.

Application filed August 13, 1925. Serial No. 49,900.

This invention relates to a bank and a bank lock and particularly to a bank lock for pocket banks. It has for one object to provide a pocket bank or coin receptacle of a

5 generally flat and book like shape, which is locked and from which coins cannot be withdrawn in any unauthorized way and which is convenient and small to be carried in the pocket. Another object is to provide a lock 10 which cannot be opened from the outside except by a key and which will lock the lid of the bank at a plurality of points. Other objects will appear from time to time throughout the specification and claims.

15 My invention is illustrated more or less diagrammatically in the accompanying drawings, wherein:

Figure 1 is a perspective view of the bank open;

20 Figure 2 is a vertical cross section on the line 2—2 of Figure 1;

Figure 3 is a horizontal section on an enlarged scale taken on the line 3—3 of Figure 2; showing the lock in locking position;

25 Figure 4 is a fragmentary section showing one of the locking lugs or hooks in the unlocked position;

Figure 5 is a sectional view on an enlarged scale taken on line 5—5 of Figure 2 showing 30 a detail of the locking mechanism;

Figure 6 is a similar view showing the parts in the unlocked position;

Figure 7 is a horizontal section taken on the line 7—7 of Figure 2;

35 Figure 8 is a vertical section taken on the line 8—8 of Figure 2 on an enlarged scale;

Figure 9 is a perspective view showing the locking member removed from the bank;

40 Figure 10 is a similar view showing one of the lock members;

Figure 11 is a view showing the lever of the locking mechanism;

Figure 12 shows the key.

Like parts are indicated by like characters throughout.

The bank is formed of a side member A having inwardly turned upper and lower flanges A¹ A¹. A² is a bottom portion fixed to the side part of the bank. A³ is an inner pocket member and A⁴ is an outer pocket member.

B is a cover provided about its edge with a downwardly and inwardly turned flange B¹. This flange at its rear end as at X is engaged between the members A³ and A⁴. It is thus permitted to swing up and down

between fixed limits, its upper movement being limited by the engagement of the flange B¹ on the flange of the member A³.

C is a coin slot formed in one end of the 60 side member A.

D is a coin trap frame. In the form here-with shown it comprises a channel extending about the coin slot and provided at suitable intervals with perforations or openings 65 D¹ in the bottom of the channel. In each of these is positioned a bead D². The beads as shown are flat members provided with downwardly extending points D³ enlarged as at D⁴ so as to provide lateral shoulders. 70 The shoulders engage the bottom of the channel portion and are thus prevented from falling through the perforations D¹ as they are wider than such perforations.

The member A is provided adjacent the 75 slot C and the slot trap with inwardly extending portions E. These parts limit the rotational or tilting movement of the beads. This is clearly shown in Figure 8 in which the lower row of beads is shown as raised 80 upon one of the members E.

The lock includes a locking plate F provided with a main inwardly bent portion F¹, a second and smaller inwardly bent portion F², and a longitudinally extended perforation F³. Adjacent its ends are two forwardly extending locking lugs or points F⁴. The member F also has formed in it, in what is normally its upper edge, a notch F⁵, and at one end an inwardly extending spring engaging hook F⁶. The locking plate F is mounted in the position shown and in contact with the casing A; the locking hooks F⁴ extending through openings A⁵ A⁵.

Between the casing member A and the locking plate F is a wedge plate G. It is provided as shown with an inwardly extending lock G¹ and normally lies within the notch F⁵ in the plate F. It is formed with an inclined upper face and provided with cam face G² terminating in a downwardly extending hook G³.

H is a spring holding plate provided with a rearwardly or inwardly bent portion H¹ and a perforation H² which preferably has formed on it an upraised flange H³. It has formed about one end a spring enclosing socket H⁴, adjacent the inner end of which is a perforation H⁵.

I is a helical spring mounted within the 110 socket or pocket H⁴ having an end I¹ extending through the perforation H⁵ and en-

gaging at its other end the hook F^6 on the member F .

J is a key formed as shown in Figure 12 and provided with a tongue J^1 .

5 The plate H itself is a spring and it is pulled inwardly from the side wall or casing part A , its two ends being forced outwardly against the locking member F and tending to force the hook members F^4 outwardly.

10 Although I have shown an operative device, still it will be obvious that many changes might be made in size, shape and arrangement of parts without departing materially from the spirit of my invention; 15 and I wish therefore that my showing be taken as in a sense diagrammatic.

The use and operation of my invention are as follows:

Assuming that the bank is open in the 20 position shown in Figure 1, with the locking parts in the locking position, it will be obvious that the cover of the bank cannot be closed until the locking parts are withdrawn. In order to do this a key is inserted in the key hole shown in the front of the bank, and it is turned so that the tongue J^1 of the key contacts first the cam face G^2 of the member G and then the hook G^3 ; and as the key is rotated in this direction, the member 25 G^2 is tilted from the position shown in Figure 2 to that shown in Figure 6 and it is forced laterally to the left as shown. Since it engages the member F through the engagement of the point G^1 in the notch F^5 , 30 the member F is moved laterally to the left as shown in the figure. This movement is in opposition to the spring action of the member H and also to that of the spring I . The 35 spring member H having its ends bearing against the plate F adjacent the locking points F^4 , F^4 tends to hold them against withdrawal inwardly and the spring I tends to hold the plate F against lateral movement. The operation of the key therefore 40 moves the plate F and the points F^4 laterally 45 against the resistance of the spring plate H and the spring I .

When the lateral movement has been continued until the inclined outer face F^7 of the hooks F^4 contact the sides of the perforations through which they extend, further continuous movement causes the hooks to be withdrawn into the bank into the position shown particularly in Figure 4. The lid of 50 the bank may then be moved to the closed position, the key permitted to return to its original position largely under the influence of the spring of the locking hooks, and then under the influence of the spring is moved 55 outward and engages the lid of the bank, holding it in the locked position. This is the position shown in full lines in Figure 2; and the position of the locking hooks is particularly shown in Figure 3. In order 60 to unlock the bank, the same operation is 65

carried out. The locking hooks being withdrawn by manipulation of the key, the bank will then be open.

The operation of the slot trap is as follows: When the bank is upright the beads 70 hang downward and do not interfere with the insertion of coins into the slot. If the bank is laid on its side, as shown especially in Figures 2 and 8, one row of beads falls downward into one of the members E and 75 the other row extends downward across the slot, the ends of the two rows overlapping each other. In this position one of the rows of beads is always across the slot, preventing withdrawal of coins. 80

I claim:

1. In combination with a bank having a casing and a movable lid, means for locking the lid closed, said means including a hook extending beyond the casing of the 85 bank and adapted to engage a portion of the lid, said hook provided with a cam face, and means for moving said hook whereby said face contacts a fixed portion of the bank, and as it is thereafter moved is withdrawn within the bank to unlock the same. 90

2. In combination with a bank having a 95 casing and a movable lid, means for locking the lid closed, said means including a hook extending beyond the casing of the bank, and adapted to engage a portion of the lid, said hook provided with a cam face, and means for moving said hook whereby said face contacts a fixed portion of the bank, and as it is thereafter moved is withdrawn within the bank to unlock the same, and means for forcing said hook outwardly beyond said casing. 100

3. In combination with a bank having a 105 casing and a movable lid, means for locking the lid closed, said means including a hook extending beyond the casing of the bank and adapted to engage a portion of the lid, said hook provided with a cam face, and means for moving said hook whereby said face contacts a fixed portion of the bank, and as it is thereafter moved is withdrawn within the bank to unlock the same, and spring 110 means for forcing said hook outwardly beyond said casing. 115

4. In combination with a bank having a 120 casing and a movable lid, means for locking the lid closed, said means including a hook extending beyond the casing of the bank and adapted to engage a portion of the lid, said hook provided with a cam face, and means for moving said hook whereby said face contacts a fixed portion of the bank, and as it is thereafter moved is withdrawn within the bank to unlock the same, and means for forcing said hook outwardly beyond said casing, and additional means for resisting 125 such movement of the locking hook. 130

5. In combination with a bank having a 130 casing and a movable lid, means for locking

the lid closed, said means including a hook extending beyond the casing of the bank and adapted to engage a portion of the lid, said hook provided with a cam face, and means for moving said hook whereby said face contacts a fixed portion of the bank, and as it is thereafter moved is withdrawn within the bank to unlock the same, and spring means for forcing said hook outwardly beyond said casing, and additional means for resisting such movement of the locking hook.

6. In combination with a bank having a casing and a movable lid, means for locking the lid closed, said means including a hook extending beyond the casing of the bank and adapted to engage a portion of the lid, said hook provided with a cam face, and means for moving said hook whereby said face contacts a fixed portion of the bank, and as it is thereafter moved is withdrawn within the bank to unlock the same, and spring means for forcing said hook outwardly beyond said casing, and additional means for resisting such movement of the locking hook.

7. In combination with a bank having a casing and a movable lid, means for locking the lid closed, said means including a plurality of locking hooks extending beyond the casing of the bank and adapted to engage a portion of the lid, each provided with a cam face, and means for moving said hooks laterally in unison, whereby said face contacts a fixed portion of the bank, and as it is thereafter moved is withdrawn within the bank to unlock the same.

8. In combination with a bank having a casing and a movable lid, means for locking the lid closed, said means including a plurality of locking hooks extending beyond the casing of the bank and adapted to engage a portion of the lid, each provided with a cam face, and means for moving said hooks laterally in unison, whereby said face contacts a fixed portion of the bank, and as it is thereafter moved is withdrawn within the bank to unlock the same, and means for forcing said hook outwardly beyond said casing.

9. In combination with a bank having a casing and a movable lid, means for locking the lid closed, said means including a plurality of locking hooks extending beyond the casing of the bank and adapted to engage a portion of the lid, each provided with a cam face, and means for moving said hooks laterally in unison, whereby said face contacts a fixed portion of the bank, and as it is thereafter moved is withdrawn within the bank to unlock the same, and spring means for forcing said hook outwardly beyond said casing.

10. In combination with a bank having a casing and a movable lid, means for lock-

ing the lid closed, said means including a plurality of locking hooks extending beyond the casing of the bank and adapted to engage a portion of the lid, each provided with a cam face, and means for moving said hooks laterally in unison whereby said face contacts a fixed portion of the bank, and as it is thereafter moved is withdrawn within the bank to unlock the same, and means for forcing said hook outwardly beyond said casing, and additional means for resisting such movement of the locking hook.

11. In combination with a bank having a casing and a movable lid, means for locking the lid closed, said means including a plurality of locking hooks extending beyond the casing of the bank and adapted to engage a portion of the lid, each provided with a cam face, and means for moving said hooks laterally in unison, whereby said face contacts a fixed portion of the bank and as it is moved thereafter is withdrawn within the bank to unlock the same, and spring means for forcing said hook outwardly beyond said casing, and additional means for resisting such movement of the locking hook.

12. In combination with a bank having a casing and a movable lid, means for locking the lid closed, said means including a plurality of locking hooks extending beyond the casing of the bank and adapted to engage a portion of the lid, each provided with a cam face, and means for moving said hooks laterally in unison, whereby said face contacts a fixed portion of the bank, and as it is thereafter moved is withdrawn within the bank to unlock the same, and spring means for forcing said hook outwardly beyond said casing, and additional spring means for resisting such movement of the locking hook.

13. In combination a bank comprising a casing and a movable lid, means for locking the lid closed, said means including a locking member having a plurality of locking hooks, the member being mounted within the bank and the hooks extending outwardly beyond its wall, a spring member tending normally to force the hooks beyond the wall, and an additional spring member tending to resist lateral movement of the hook carrying plate lever means adapted to be acted upon by a key, and to move the hook carrying plate laterally, the hooks being provided with cam faces adapted to contact portions of the casing whereby when the lateral movement is carried sufficiently far, they are withdrawn from the locking position into the casing.

Signed at Chicago county of Cook and State of Illinois, this 10th day of August 1925.

ARTHUR C. PRINCE.
